UNITED STATES PATENT OFFICE.

BEULAH GYBBON SPILSBURY, OF MINNEAPOLIS, MINNESOTA, ASSIGNOR TO THE MUNSINGWEAR CORPORATION, OF MINNEAPOLIS, MINNESOTA, A CORPORATION OF MINNESOTA.

LADY'S UNDERGARMENT.

Application filed November 6, 1920. Serial No. 422,259.

To all whom it may concern:

Be it known that I, BEULAH GYBBON SPILSBURY, a citizen of the United States, resident of Minneapolis, county of Hennepin, State of Minnesota, have invented certain new and useful Improvements in Ladies' Undergarments, of which the following is a specification.

In making ladies' undergarments of a woven fabric and of the style where the opening down the front and buttons therefore are omitted, adapting the garment to be worn with thin outer clothing, the manufacturer is confronted with the problem of providing a garment that can be drawn up easily over the hips without an excess of material at the bust, the difference in measurement being usually about five inches. Evidently in a buttonless garment of the type to be drawn over the hips the bust measure must at least equal the hip measurement and while this surplus fabric around the bust line is not necessarily a disadvantage when properly distributed around the body, it is some inconvenience to the wearer to distribute it evenly.

Furthermore, in a buttonless garment or one having no opening down the front of this type, the shoulder straps must be of sufficient length to allow the garment to be drawn up over the hips and at the same time these straps must not be too far apart to inconvenience the wearer or of such a length that the top of the garment will be too low or too far down on the bust.

The object, therefore, of my invention is to provide a woven fabric undergarment having no front opening or row of buttons down the front, which can be pulled up easily over the hips, and in which the necessary fullness at the bust is permanently distributed.

The invention consists generally in various constructions and combinations, all as hereinafter described and particularly pointed out in the claims.

In the accompanying drawings forming part of this specification,

Figure 1 is a view of the upper portion of the garment, illustrating the fit on the bust of the wearer.

Figure 2 is a perspective view of the garment, showing how it is opened at the top to provide for drawing up over the hips,

Figure 3 is a similar view, showing the

manner of utilizing the full length of the shoulder straps temporarily when the garment is being put on.

Figure 4 illustrates the upper portion of the garment showing the band in its raised position on the shoulder straps and indicating how the opening of the placket would be restricted if the strap was attached to the upper edge of the band.

Figure 5 is a similar view showing the band pushed down or crumpled on the end of the strap and indicating how this arrangement allows the placket to be opened wide without being restricted by the shoulder strap.

In the drawing, 2 represents the upper portion of a woven fabric undergarment. A band 3, equal in length to the bust measure, is sewed into the top of this garment, and on this band is permanently gathered the excessive fullness of fabric that is necessary in buttonless garments. To provide necessary room to draw this garment up over the hips, a placket opening 4 is provided under the arm, extending to a point well below the band. One end of the band has buttons 5 and the other end buttonholes 6 for joining the ends of the band together and closing the placket when the garment is in place on the wearer. Shoulder straps 7 are attached at one end to the rear of the garment and at their forward ends are laced through openings 8 and attached at 9 to the lower edge of the band. The band on the front of the garment slides or crumples on the forward ends of the straps, thereby allowing a larger opening to be formed in the garment than would be the case if the forward ends of the straps were secured to the upper edge of the band. The manner of sliding the band on the straps is indicated in Figure 3.

As indicated in Figure 4, if these straps were fastened to the top of the band, the use of the placket opening would be restricted, as the straps would not allow the sides of the placket to be opened to their fullest extent in drawing the garment up over the hips. By connecting the forward ends of the straps to the lower edge of the band and folding or crumpling the band on the straps when the placket is opened, I am able to use longer shoulder straps than would be possible if the straps were connected at both ends to the upper edge of the

band, and when the band is folded or crumpled on the straps, as indicated in Figure 5, the straps will not interfere with the opening of the placket and the convenient drawing on of the garment over the hips. Obviously, if the straps were connected at both ends to the upper edge of the band, they would restrict the free opening of the placket as indicated in Figure 4, but where the straps are connected at one end to the lower edge of the band, I may push or slide the band downwardly thereon when the garment is drawn on and then when the straps are put over the shoulders, the band may be raised on the straps and smoothed out to fit snugly around the bust with the ends joined together at the placket opening to hold the garment in place. The advantage of this arrangement lies in the fact that when the garment is to be pulled on over the hips, the method of attaching the band allows approximately two inches more length to the shoulder straps, due to the fact that the band may be slipped down on the straps about that distance to a lower point on the garment. I am thus able to provide the required opening for drawing the garment up over the hips without producing a surplus of fabric at the bust, which would cause inconvenience or discomfort to the wearer.

I claim as my invention:

1. A lady's undergarment to be pulled up over the hips having a band stitched at the top of the fabric composing the main por-

tion of the garment, said band corresponding in length to the bust measure whereby the band will lie smoothly on the bust, said band having gathered thereon the fullness of said fabric necessary in garments of this type, the garment having a placket opening under the arm below the band, the ends of said band having a fastening means for closing the placket opening and shoulder straps attached only to the lower edge of the band, said straps being just long enough to pass over the hips of the wearer.

2. A lady's undergarment adapted to be pulled up over the hips having a band with holes therein, said band being stitched to the top of the garment, said band corresponding in length to the bust measure whereby it will lie smoothly on the wearer's bust, said band having gathered thereon the fullness of the fabric necessary in garments of this type, the garment having a placket opening under the arm below the band, the ends of said band having a fastening means for closing the placket opening and shoulder straps passing through said holes and attached to the lower edge of the band, said straps being just long enough to pass the hips of the wearer when the band crumples between the holes and the points of attachment of said band and straps.

In witness whereof, I have hereunto set my hand this 29th day of October, 1920.

BEULAH GYBBON SPILSBURY.
